UNITED STATES PATENT OFFICE.

DAVID F. STAUFFER, OF YORK, PENNSYLVANIA.

DESIGN FOR A CRACKER.

SPECIFICATION forming part of Design No. 16,848, dated August 10, 1886.

Application filed March 29, 1886. Serial No. 197,043. Term of patent 14 years.

To all whom it may concern:

Be it known that I, DAVID F. STAUFFER, a citizen of the United States, residing at York, in the county of York and State of Pennsylvania, have invented a new and original Design for Crackers or Pretzels, of which the following is a specification, reference being had to the accompanying drawings, forming part thereof.

10 In the said drawings, Figure 1 represents a plan view of my newly-designed pretzel; and Fig. 2, a transverse sectional view of same, taken on line xx of Fig. 1.

The leading feature of my design consists of 15 a crescent-shaped pretzel having its edges and ends rounded, as shown in the drawings. The body of the pretzel is rounded and oblong in

cross-section, and decreases in diameter from the middle to each end, where it terminates in a point, the portions between the middle and 20 such ends having ornamental indentations.

I claim—

The design for a pretzel herein shown and described, the same consisting of a crescent-shaped body rounded and oblong in cross-section, and decreasing in diameter from the middle to the ends, where it terminates in points, the body having ornamental indentations, substantially as specified.

D. F. STAUFFER.
